US00D436181S

(12) **United States Design Patent** (10) Patent No.: **US D436,181 S**
Lazio (45) Date of Patent: ** Jan. 9, 2001

(54) **COMBINED ACUPRESSURE AND MASSAGE DEVICE**

(76) Inventor: **Thomas F. Lazio**, 5646 S. Lakeview St., Littleton, CO (US) 80120

(**) Term: **14 Years**

(21) Appl. No.: **29/118,806**

(22) Filed: **Feb. 16, 2000**

Related U.S. Application Data

(63) Continuation-in-part of application No. 29/100,329, filed on Feb. 9, 1999, now Pat. No. Des. 423,676.

(51) **LOC (7) Cl.** **24-04**

(52) **U.S. Cl.** **D24/214**
